UNITED STATES PATENT OFFICE

161,525

RUG SAMPLE DISPLAY RACK

Oliver Ware Patterson, Oswego, Ill., and Kenneth H. Bowen, Auburn, N. Y., assignors to Nye-Wait Company, Inc., Auburn, N. Y., a corporation of New York

Application June 14, 1950, Serial No. 10,523

Term of patent 14 years

(Cl. D80—9)

To all whom it may concern:

Be it known that we, Oliver Ware Patterson and Kenneth H. Bowen, both citizens of the United States of America, residing at Oswego, in the county of Kendall, State of Illinois, and at Auburn, in the county of Cayuga, State of New York, respectively, have invented a new, original, and ornamental Design for Rug Sample Display Rack, of which the following is a specification, reference being had to the accompanying drawing, forming part hereof.

We claim:

The ornamental design for a rug sample display rack, as shown.

OLIVER WARE PATTERSON.
KENNETH H. BOWEN.
